Primary Examiner—Marcus A. Jackson
Attorney, Agent, or Firm—Todd N. Hathaway[57] **CLAIM**

The ornamental design for a roadside address post, as shown and described.

DESCRIPTION

FIG. 1 is a perspective view of a roadside address post showing my new design, with the broken line showing for illustrative purposes only and forming no part of the claimed design;

FIG. 2 is a front elevational view thereof, with the inside portion omitted for clarity of illustration only;

FIG. 3 is a right side elevational view thereof;

FIG. 4 is a rear elevational view thereof;

FIG. 5 is a left side elevational view thereof;

FIG. 6 is a top plan view thereof; and,

FIG. 7 is a bottom plan view thereof.
